UNITED STATES PATENT OFFICE.

HORACE W. ULRICH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,337,297.

Specification of Letters Patent. Patented Apr. 20, 1920.

Application filed May 11, 1918. Serial No. 233,824.

To all whom it may concern:

Be it known that I, HORACE W. ULRICH, a citizen of the United States, residing at East Orange, in the county of Essex, State of New Jersey, have invented certain new and useful Improvements in Telephone-Exchange Systems, of which the following is a full, clear, concise, and exact description.

This invention relates to telephone exchange systems, and more particularly to such systems employing trunk circuits for completing connections between telephone lines terminating at different switchboards.

An object of this invention is the provision of improved signaling means for such systems.

In accordance with this invention, a trunk circuit is provided with a signal control relay whose operating circuit is partially established upon connection being made with the incoming end of the trunk circuit, and is completely established upon the disconnection of a link circuit from the outgoing end, thereby to cause the operation of a signaling device associated with the link circuit connected with the incoming end.

For a more complete understanding of this invention, reference should be had to the following description considered in connection with the accompanying drawing illustrating one embodiment thereof.

As shown in the drawing, a telephone line A extends to and terminates at a switchboard at which is located a link circuit B, which may be connected with the telephone line A in any suitable and well-known manner. A trunk circuit C extends from this first switchboard to a second switchboard at which is located a link circuit D for establishing connections between the trunk circuit C and a telephone line E terminating at the second switchboard. The link circuits B and D may, of course, be employed for interconnecting telephone lines similar to those which are shown terminating at the respective switchboards. The apparatus shown to the left of the dotted line 1-1 is located at the first switchboard which may be designated as X, and that shown to the right of this dotted line may be located at the second switchboard designated as Y.

The operator at switchboard X having actuated the listening key 6 to connect the telephone set with the calling telephone line

A, receives instructions that connection is desired with a telephone line, for example, line E, which terminates at the switchboard Y. The listening key 6 may then be restored to normal position and plug 7 of the cord circuit B inserted in jack 8 of the trunk circuit C. Lamp 9 lights, and relay 10 and cutoff relay 15 operate over a circuit from battery through the lamp 9, winding of relay 10, sleeve contacts of the plug 7 and the jack 8, and the winding of cutoff relay 15 to ground. Relay 10, in operating, causes the energization of ringing relay 11 over a circuit from battery through resistance 12, winding of ringing relay 11, normal contact of relay 16, contact of trip relay 13 and the contact of relay 10 to ground. Ringing relay 11, upon being energized, connects the source of ringing current 14 with the trunk circuit for causing the operation of relay 56 over a circuit from the source of ringing current 14 through the winding of trip relay 13, lower alternate contact of ringing relay 11, ring contacts of the plug 7 and the jack 8, lower normal contact of relay 17, condenser 18, normal contact and winding of relay 56, the lower contact of relay 19 and resistance 20 to ground. Relay 56, in operating, completes a locking circuit for itself from battery through the upper alternate contact and winding of relay 16, the lower contact of relay 19 and resistance 20 to ground. The operation of relay 56 also causes lamp 21 to be lighted to furnish a signal to the operator at the switchboard Y. The operation of the cutoff relay 15 disconnects line relay 22 from bridged relation to the talking conductors of the trunk circuit C.

The operator at switchboard Y, upon observing the lighted condition of the lamp 21, inserts plug 23 of cord circuit D into jack 24 of the trunk circuit C, whereupon relay 19 and marginal relay 25 operate over a circuit from battery through lamp 26, normal contact of supervisory relay 27, sleeve contacts of the plug 23 and the jack 24, and the windings of relays 19 and 25 to ground. The operation of relay 19 opens its lower contact, thereby releasing relay 56 to extinguish the lamp 21. The closure of the lower contact of relay 25 connects resistance 28 in series with supervisory relay 29, to provide a low impedance path for ringing current

- for causing the operation of trip relay 13. This circuit may be traced from the source of ringing current 14 through the winding of trip relay 13, lower alternate contact of 5 ringing relay 11, ring contacts of the plug 7 and the jack 8, lower normal contact of relay 17, winding of supervisory relay 29, lower contact of relay 25, resistance 28 and the upper normal contact of relay 17 to ground.
- 10 Trip relay 13, upon operating, opens the short circuit about the winding of relay 16, which in turn is energized to open its normal contact in the previously mentioned short circuit, and to close its alternate contact, thereby establishing a short circuit 15 about the winding of ringing relay 11 and providing a locking circuit for itself. Ringing relay 11 immediately releases its armatures, disconnecting the source of ringing current 14 from the trunk circuit.
- 20 Upon the closure of the normal contacts of ringing relay 11, supervisory relays 29 and 33 operate over a circuit from battery through the winding of supervisory relay 33, 25 lower normal contact of ringing relay 11, ring contacts of the plug 7 and the jack 8, lower normal contact of relay 17, winding of supervisory relay 29, lower contact of relay 25, resistance 28 and the upper normal 30 contact of relay 17 to ground. Supervisory relay 33, in operating, establishes a shunt circuit including resistance 12 about the lamp 9, thereby extinguishing this lamp. Supervisory relay 29, in operating, opens 35 the short circuit about the winding of relay 17, whereupon this relay operates over a circuit from battery through the upper contact of relay 19, resistance 34 and the winding of relay 17 to ground. Upon the operation of relay 17, the normal contacts thereof are opened, and the alternate contact closed, whereupon supervisory relays 33 and 29 are maintained energized over a circuit from battery through the winding 40 of relay 33, lower normal contact of ringing relay 11, ring contacts of the plug 7 and the jack 8, lower left-hand winding of repeating coil 35, winding of supervisory relay 29, lower contact of relay 25, resistance 28, alternate contact of relay 17, upper left-hand winding of repeating coil 35, tip contacts of the jack 8 and the plug 7, and the upper normal contact of ringing relay 11 to ground. The operation of relay 25 causes 45 the closure of its upper contact, thereby partially establishing an operating circuit for relay 36. The winding of this relay 36 is normally short-circuited through the middle normal contact of relay 17, and while 50 relay 17 is operated, the short circuit about the winding of relay 36 is maintained through the alternate contact of supervisory relay 29, which operates prior to the operation of relay 17. The insertion of the plug 55 23 into the jack 24 also causes the operation of cord and trunk supervisory relays 27 and 37 over a circuit from battery through the winding of supervisory relay 27, ring contacts of the plug 23 and the jack 24, lower right-hand winding of the repeating 50 coil 35, left-hand low resistance winding of the trunk supervisory relay 37, left-hand contact of relay 36, upper right-hand winding of repeating coil 35 and the tip contacts of the jack 24 and the plug 23 to ground. The operation of cord supervisory relay 27 removes the short circuit from resistance 38, and establishes a short circuit for the lamp 26. The resistance of the lamp 26 and the resistance coil 38 are about equal, 55 so that the exclusion of one from and the inclusion of the other in the sleeve circuit, has no effect upon the relays 19 and 25. The operation of the trunk supervisory relay 37 closes its contact which is in multiple 60 with the lower contact of relay 25.
- The operator at switchboard Y may actuate listening key 39 to connect the operator's telephone set in circuit. The actuation of this listening key 39 causes the closure of the middle contact thereof, whereupon marginal relay 25 releases its armatures. This is brought about by including resistance 41 in parallel with the windings of relays 19 and 25, upon the closure of the 65 middle contact of the listening key 39. The release of this marginal relay 25 at this time has no effect upon the apparatus of the trunk circuit. The reason for releasing this relay 25 when the listening key 39 is actuated will 70 more fully hereinafter appear.
- Upon being advised that connection is desired with the line of subscriber E, the operator at the switchboard Y restores the listening key 39 to normal condition, whereupon marginal relay 25 attracts its armatures. The operator may then insert calling plug 45 of the cord circuit D into jack 46 of the telephone line E, whereupon calling 75 supervisory lamp 47 lights and cut off relay 48 operates over a circuit from battery through the lamp 47, normal contact of the calling supervisory relay 49, sleeve contacts of the plug 45 and the jack 46, and the winding of cutoff relay 48 to ground. The operation of the cutoff relay disconnects the line relay 50 from the line. The operator may thereupon actuate ringing key 51 to connect the source of ringing current 80 with the line for operating the usual call bell at the station. Upon the removal of the receiver by subscriber E, in response to the operation of the call bell, supervisory relay 49 is operated to open the short circuit about resistance 52 and to establish a short 85 circuit for the lamp 47 which is thereby extinguished. At the conclusion of the conversation, the subscribers restore the receivers to the switchhooks, thereby causing the appropriate supervisory lamps of the asso- 90

ciated cord circuits to furnish disconnect signals to the operators. The operators may thereupon withdraw the plugs from the jacks, restoring all apparatus to normal condition.

If the operator at switchboard Y does not actuate the listening key 39, after inserting the plug 23 into the jack 24, the answering operator's telephone set will not be connected in circuit when the originating operator's set is connected in circuit by the actuation of the listening key 6. It will be necessary, therefore, for the originating operator to rering or resign the answering operator. This may be done by withdrawing the plug 7 from and reinserting it into the jack 8. The withdrawal of the plug 7 from the jack 8 causes the restoration of all the apparatus of the cord circuit, and the release of cutoff relay 15 and supervisory relay 29 of the trunk circuit. Relay 29, in releasing its armature, opens the short circuit about the winding of relay 36, which thereupon operates over a circuit from battery through the upper contact of marginal relay 25, resistance 53 and the winding of relay 36 to ground. Relay 36, in operating, opens its contacts. The opening of the right-hand contact prevents the reestablishment of the short circuit about its winding when supervisory relay 29 again operates. The opening of the left-hand contact of relay 36 opens the short circuit about the right-hand high resistance winding of relay 37, thereby increasing the resistance in circuit with the cord supervisory relay 27. Cord supervisory relay 27 thereupon releases its armatures to remove the short circuit from the lamp 26, and to establish a short circuit for the resistance 38. The lamp thereupon lights to furnish a signal to the answering operator. The reinsertion of the plug 7 into the jack 8 causes the operation of relays 10 and 11 of the cord circuit to connect the source of ringing current to the trunk circuit, whereupon trip relay 13 immediately operates, causing the operation of locking relay 16 which releases ringing relay 11 to disconnect ringing current from the trunk circuit. Supervisory relays 33 and 29 thereupon operate. The operator at the switchboard Y, observing the lighted condition of the lamp 26 actuates listening key 39 to connect the operator's telephone set 40 in circuit. The closure of the middle contact of this listening key 39 releases marginal relay 25, which in opening its upper contact, causes the de-energization of relay 36. Upon the closure 60 of the right-hand contact of relay 36, the short circuit about the winding thereof is immediately established. The closure of the left-hand contact of relay 36 short-circuits the high resistance winding of the trunk supervisory relay 37 to cause the operation

of cord supervisory relay 27 which extinguishes the supervisory lamp 26.

What is claimed is:

1. A telephone exchange system comprising a trunk circuit extending from a first to a second switchboard, a link circuit at the first switchboard, a signaling device at the second switchboard operated upon connection of the link circuit with the trunk circuit, a link circuit at the second switchboard, a signal control relay, an operating circuit therefor partially established upon the connection of the second link circuit with the trunk circuit, and means responsive to the disconnection of the first link circuit from the trunk circuit for completing the partially established operating circuit.

2. A telephone exchange system comprising a trunk circuit extending from a first to a second switchboard, a link circuit at the first switchboard, a signaling device at the second switchboard operated upon connection of the link circuit with the trunk circuit, a link circuit at the second switchboard, a relay associated with the trunk circuit, an operating circuit therefor partially established upon the connection of the second link circuit with the trunk circuit, a relay in the trunk circuit responsive to the disconnection of the first link circuit from the trunk circuit for completing the partially established operating circuit, and a signaling device in the connected second link circuit controlled by the first mentioned relay.

3. A telephone exchange system comprising a trunk circuit extending from a first to a second switchboard, a link circuit at the first switchboard, a signaling device at the second switchboard operated upon connection of the link circuit with the trunk circuit, a link circuit at the second switchboard, a relay in the trunk circuit, a low resistance circuit normally connected in shunt with the relay, an operating circuit for the relay, means responsive to the connection of the second link circuit with the trunk circuit for closing a contact in the operating circuit, means responsive to the disconnection of the first link circuit from the trunk circuit to open the low resistance circuit, thereby to cause the operation of the relay, and a signaling device controlled by the relay.

4. A telephone exchange system comprising a trunk circuit extending from a first to a second switchboard, a link circuit at the first switchboard, a signaling device at the second switchboard operated upon connection of the link circuit with the trunk circuit, a link circuit at the second switchboard, a signal control relay, an operating circuit therefor partially established upon the connection of the second link circuit with the trunk circuit, means responsive to the disconnection of the first link circuit with the trunk circuit for completing the partially

established operating circuit, and an operator controlled switch in the second link circuit for causing the opening of the operating circuit.

5. A telephone exchange system comprising a trunk circuit extending from a first to a second switchboard, a link circuit at the first switchboard, a source of ringing current, means in the link circuit responsive to 70 the connection thereof with the trunk circuit for connecting therewith the source of signaling current, a signaling device at the second switchboard operating upon the connection of the ringing current with the trunk circuit, a link circuit at the second switchboard, a signal control relay, an operating circuit therefor partially established upon the connection 75 of the second link circuit with the trunk circuit, means responsive to the disconnection of the first link circuit with the trunk circuit for completing the partially established operating circuit.

6. A telephone exchange system comprising 80 a trunk circuit extending from a first to a second switchboard, a link circuit at the first switchboard, a source of ringing current, means in the link circuit responsive to the connection thereof with the trunk circuit for connecting therewith the source of 85 ringing current, a signaling device at the second switchboard operating upon connection of the ringing current with the trunk circuit, a link circuit at the second switchboard, a relay in the trunk circuit, a low resistance circuit connected in shunt of the 90 relay, an operating circuit for the relay, a relay energized upon connection of the second link circuit with the trunk circuit for 95 closing a contact in the operating circuit, means responsive to the disconnection of the first link circuit from the trunk circuit for 100 opening the shunt circuit, thereby to cause the operation of the first relay, a signaling device in the second link circuit operating 105 upon the operation of the first-mentioned relay, an operator's telephone set at the second switchboard, a listening switch for connecting the operator's telephone set with the 110 second link circuit, and a shunt circuit for the second-mentioned relay established by the operation of the listening switch for 115 causing the release of the second-mentioned relay, thereby to open the operating circuit of the first-mentioned relay.

7. A telephone exchange system comprising 120 a trunk circuit extending from a first to a second switchboard, a link circuit at the first switchboard, a source of ringing current, means in the link circuit responsive to 125

the connection thereof with the trunk circuit for connecting therewith the source of ringing current, a signaling device at the second switchboard operating upon the connection of the ringing current with the trunk circuit, a link circuit at the second switchboard, a signal control relay, a second relay in the trunk circuit responsive to the connection of the second link circuit therewith for causing the disconnection of ringing current from the trunk circuit, an operating circuit for the signal control relay partially established upon the response of the second relay, and means responsive to the disconnection of the first link circuit from the trunk circuit for 130 completing the partially established operating circuit.

8. A telephone exchange system comprising a trunk circuit extending from a first to a second switchboard, a link circuit at the first switchboard, a source of ringing current, means in the link circuit responsive to the connection thereof with the trunk circuit for connecting therewith the source of ringing current, a signaling device at the second switchboard operating upon the connection of the ringing current with the trunk circuit, a link circuit at the second switchboard, a relay in the trunk circuit responsive to the connection of the second link circuit therewith for causing the disconnection of the ringing current from the trunk circuit, a second relay, an operating circuit therefor partially established upon the response of the first relay, and a relay responsive to the disconnection of the first link circuit from the trunk circuit for completing the partially established operating circuit of the second relay, and a signaling device in the connected second link circuit 140 controlled by the second relay.

9. A telephone exchange system comprising a trunk circuit extending from a first to a second switchboard, a link circuit at the first switchboard connected with the trunk circuit, a signal control relay in the trunk circuit, a link circuit at the second switchboard, an operating circuit for the signal control relay partially established upon the connection of the second link circuit with the trunk circuit, means responsive to the disconnection of the first link circuit from the trunk circuit for completing the partially established operating circuit.

10. A telephone exchange system comprising a trunk circuit extending from a first to a second switchboard, a link circuit at the first switchboard connected with the trunk circuit, a signal control relay in the trunk circuit, a link circuit at the second switchboard, a second relay in the trunk circuit responsive to the connection of the second link circuit with the trunk circuit, an operating circuit for the signal control relay partially established upon the response of the second 150

relay, and a third relay responsive to the disconnection of the first link circuit from the trunk circuit for completing the partially established operating circuit of the 5 signal control relay.

11. A telephone exchange system comprising a trunk circuit extending from a first to a second switchboard, a link circuit at the first switchboard connected with the trunk circuit, a signal control relay in the trunk circuit, a link circuit at the second switchboard, a low resistance circuit normally connected in shunt of the signal control relay, an operating circuit for the signal control 10 relay, a second relay in the trunk circuit responsive to the connection of the second link circuit therewith for closing a contact in the operating circuit, and a relay responsive to the disconnection of the first link circuit from the trunk circuit for opening the normally closed low resistance circuit, thereby causing the operation of the signal control 15 relay.
12. A telephone exchange system comprising a trunk circuit extending from a first to a second switchboard, a link circuit at the 20

first switchboard connected with the trunk circuit, a signal control relay in the trunk circuit, a link circuit at the second switchboard, a low resistance circuit normally connected in shunt of the signal control relay, an operating circuit for the signal control 25 relay, a second relay in the trunk circuit responsive to the connection of the second link circuit therewith for closing a contact in the operating circuit, a relay responsive to the disconnection of the first link circuit from the trunk circuit for opening the normally closed low resistance circuit, thereby causing the operating of the signal control 30 relay, a signaling device in the connected second link circuit operating upon the operation of the signal control relay, an operator's telephone set, a listening switch controlling the connection thereof with the second link circuit, and means responsive to the actuation of the listening switch for rendering the operating circuit ineffective.

In witness whereof I hereunto subscribe my name this 7th day of May, A. D. 1918. 50

HORACE W. ULRICH.
